UNITED STATES PATENT OFFICE.

JOSEPH LEDERER, OF NEW YORK, N. Y.

DESIGN FOR AN INVERTED GAS-LAMP.

No. 38,832.

Specification for Design.

Patented Sept. 24, 1907.

Application filed August 5, 1907. Serial No. 387,245. Term of patent 7 years.

To all whom it may concern:

Be it known that I, JOSEPH LEDERER, a citizen of the United States, and residing at No. 253 West One Hundred and Twenty-first street, New York city, in the county of New York and State of New York, have invented a new, original, and ornamental Design for Inverted Gas-Lamps, of which the following is a specification, reference being had to the accompanying drawing, forming part thereof.

The figure is a plan view of an inverted gas lamp showing my new design.

I claim:

The ornamental design for an inverted gas lamp as shown in the said drawing.

JOSEPH LEDERER.

Witnesses:

HERMAN PHILLIPS,
WILLIAM GROSSMAN.
